UNITED STATES PATENT OFFICE.

JOSEPH C. DITTRICH, OF BROOKLYN, NEW YORK.

LINE-UP REGISTER GAUGE.

Application filed October 18, 1921. Serial No. 508,444.

To all whom it may concern:

Be it known that I, JOSEPH C. DITTRICH, a citizen of the United States, and a resident of New York, borough of Brooklyn, 5 in the county of Queens and State of New York, have invented certain new and useful Improvements in a Line-Up Register Gauge, of which the following is a full, clear, and exact specification.

10 This invention relates more particularly to a class of devices designed to be used in the art of printing.

My invention has for its object primarily to provide a device or gauge for employment especially in conjunction with the work of making-up forms of type composition in chases so that printing of the pages of books, magazines and other publications may be accurately executed by the forms of type 20 in one chase for printing the pages of the publication being so positioned relative to the forms of type in other chases that all of the printed pages will be in exact register, in order to obviate the liability of spoilage 25 during the folding, trimming or binding of the sheets upon which the pages are printed.

The invention consists essentially of a retaining device adapted to be removably held adjacent the forms of type composition arranged in the frame of a chase, and on the retaining device is carried a register bar disposed crosswise of the chase so that its ends extend toward two of the opposite bars of the frame of the chase. Adjustably 30 movable on the end portions of the register bar may be one or two guide bars, and associated with the register bar and guide bars is a device which is operable for adjusting the guide bars to line-up the forms of type 35 composition in the chase so that the forms of one chase will be in accurate register with the forms of other chases when a number of chases with forms of type composition are used in a job of printing.

40 Other objects of the invention are to provide on the register bar an exposed scale divided into measurements as well as providing on each of the guide bars a scale divided into fractions of inches whereby the 45 positions of the forms of type composition may be indicated; and to provide means so that each of the guide bars may be removably locked when adjusted.

With these and other objects in view the 50 invention will be hereinafter more fully described with reference to the accompanying

drawings forming a part of this specification in which similar characters of reference indicate corresponding parts in all the views, and will then be pointed out in the 60 claims at the end of the description.

In the drawing, Figure 1 is a top plan of a chase with forms of type composition and showing the manner of using my improved line-up register gauge in conjunction therewith.

Fig. 2 is an enlarged fragmentary view, partly broken away, showing an inverted plan of the register bar and other parts of the device.

Fig. 3 is an enlarged fragmentary view, showing a top plan of the base-plate of the retaining device used in the gauge as removably applied on the cross center bar of the chase.

Fig. 4 is an enlarged perspective view of the parts shown in Fig. 3.

Fig. 5 is an enlarged perspective of the base-plate and clamp of the retaining device in an inverted position.

Fig. 6 is an enlarged fragmentary view, showing a detail section taken on the line 6-6 of Fig. 7.

Fig. 7 is an enlarged fragmentary view, showing a detail section taken on the line 7-7 of Fig. 6.

Fig. 8 is an enlarged top plan of part of the means used for releasably locking each of the guide bars to the register bar of the device, and

Fig. 9 is an enlarged fragmentary view, showing an inverted plan of parts of the locking means and part of the register bar as well as part of one of the guide bars.

The line-up register gauge has a retaining device 10 adapted to be removably arranged in a stationary position within a chase, as 11, of any well known make used for making-up spaced forms of type composition, as 12, though the chase illustrated 95 has a frame 13 of substantially a square or rectangular shape with crossbars, as 14 and 15, provided between the bars of the frame.

The retaining device 10 is preferably 105 composed of a base-plate 16 of substantially a rectangular shape, and on the underside of this base-plate is a clamp 17 which may be of any suitable type, though the clamp shown consists of providing at the ends of the plate two pairs of spaced depending yielding clips or fingers, as 18, 18^a and 110

19, 19^a. The fingers may be in the forms 5 of strips of flat spring metal one protruding downwardly from each corner of the plate, and the free end parts of the strips of each pair are bent inwardly toward each other under the plate 16 as well as being spaced apart so that they may be removably sprung in straddle arrangement over the crossbars 14 and 15 of the 10 chase 11 when the base-plate 16 is applied to the chase, the spring strips being tensioned to clamp the bar of the chase for releasably holding the plate against accidental separation from the bar. Protruding 15 upwardly from the top face of the base-plate 16 are cross ribs, as 20, for being removably received into communicating cross sockets, as 21, provided in the underside of a supporting plate 22 forming part of the 20 retaining device 10, and this supporting plate may be of a similar size and shape to that of the base-plate 16.

The supporting plate 22 is fixed on the underside of a short bar or strip, as 22^a, which 25 is secured by a sleeve, as 22^b, to the underside of a register bar 23 which is preferably substantially square or rectangular in cross section, and this bar may be of a length so that its ends terminate at or in proximity to two 30 of the opposite bars of the frame 13 of the chase 11 when the device is in use. On the upper or exposed face of the register bar 23 is a scale, as 24, consisting of divisions, such as pica and nonpareil type measurements, in 35 order to determine the accurate positions of the forms of type composition in the chase.

Carried by the register bar 23 may be one or two corresponding guide bars, as 25 and 26, both disposed right angularly across the 40 register bar as well as being adjustably movable on the end portions of the register bar toward and from its center so that the positions of the guide bars may be determined according to the type measurements of the 45 scale 24 of the register bar 23. Each of the guide bars 25 and 26 is preferably substantially rectangular in cross section, and on the central part of the top face of each of the guide bars is a square or rectangular sleeve, 50 as 27, of a size to allow the guide bar to readily move on the register bar without tendency to shift from true straight movements back and forth. The guide bars 25 and 26 will thereby extend below the register 55 bar for being removably arranged between the forms of type composition in the chase 11, and the end parts of the guide bars will also extend toward the bars of the frame 13 of the chase which are at right angles to the 60 bars of the frame toward which the register bar 23 extends. On the top or exposed face of each of the adjustable guide bars 25 and 26 may be a scale 28 consisting of divisions in inches and fractions of inches in order to 65 determine the positions of the forms of type

composition in the chase with respect to lateral directions from the register bar 23. When the device is used with a chase of large size each of the guide bars may be lengthened by detachably applying to one or both 70 of its ends extension bars, as 29 and 30. These extension bars may be of suitable lengths as well as being of widths and thicknesses corresponding to the width and thickness of each of the guide bars. In each end 75 of the guide bars 25 and 26 may be provided spaced sockets, as 31 and 32. Projecting from one of the ends of each of the extension bars may be spaced pins, as 33 and 34, adapted to be removably inserted in one of 80 the pairs of sockets 31 and 32 of one of the ends of one of the guide bars, and by applying these extension bars in this manner to the ends of the guide bars they may be 85 lengthened as occasion requires.

To permit each or both of the guide bars 25 and 26 to be adjustably moved in unison on the register bar 25 toward and from the retaining device 10 an adjusting device, as 35, is provided. This adjusting device is 90 preferably in the form of a rod having its halves right and left threaded, as at 36 and 37, and this threaded rod is rotatably seated in a groove 38 extending lengthwise throughout the underside of the register bar 23. The 95 rod 35 is of a length slightly longer than the register bar, and the central part of the rod is rotatably arranged between the supporting plate 22 of the retaining device 10 and the register bar. The ends of the rod 35 are 100 rotatably held to the ends of the register bar 23 by straps, as 39 and 40, provided in spanning arrangement across the groove 38 of the register bar and over the rod 35. One end of the rod 35 protrudes beyond an end 105 of the register bar 23, and on this protruding end of the rod may be a head, as 41, to allow the rod to be manually rotated. The threaded parts 36 and 37 are screwed 110 through threaded openings in the sleeves 27 of the guide bars 25 and 26 so that when the adjusting device or threaded rod 35 is rotated accordingly the guide bars will be moved in unison on the register bar 23 toward and from the retaining device 10. 115

Serving as means to releasably lock each of the guide bars 25 and 26 to the register bar 23, on each of the guide bars 25 and 26 attached to each of the sleeves 27 may be a lock, as 43, and each of these locks has a 120 sleeve, as 44, which is movable on the register bar 23. In the end of the lower plate of each of the sleeves 44 adjacent to the sleeve 27 is an opening 45, and spaced under this opening is the pronged end 46 of a spring strip or plate 47 having its second part bent as well as being raised to the underside of its sleeve 44. Movable inwardly and outwardly of the opening 45 of the spring strip 125 47 and held to the prongs 46 of this strip is 130

a jaw or block 48 having in its upper face a threaded groove 49 adapted to receive the threaded rod or adjusting device 35 to releasably lock the rod against rotation and 5 in turn to permit the guide bars 25 and 26 to be releasably locked to the register bar 23, as will be hereinafter more fully explained. Below the pronged spring strip 47 of the lock 43 of each of the guide bars is a plate, as 50, 10 which extends from the sleeve 27 of the guide bar of its respective lock, and in the plate 50 of each of the locks is rotatably mounted a stud, as 51, having a projecting lug or finger, as 52, adapted to be moved 15 into and out of engagement with the threaded block 48, so that the block will likewise be moved into and out of engagement with the rod 35 of the register bar 23. On one end of the stud 51 of each of the locks 43 20 is a handle, as 53, to allow the stud 51 to be rotatably moved for swinging the lug 52 into and out of engagement with the threaded block 48. The handle 53 and lug 52 of each of the locks are relatively positioned so that 25 when the handles 53 are swung upwardly the lugs 52 will engage and move the threaded grooved jaws or blocks 48 into engagement with the adjusting device or rod 35 for locking the guide bars 25 and 26 to 30 the register bar 23, and when the handle is swung downwardly the lug and groove block will be disengaged from the rod 35 for releasing the guide bars to permit of their adjustment on the register bar. If desired in 35 a threaded opening in one of the side walls of the sleeve 44 of each of the locks may be a set screw 54 adapted to be rotated into and out of engagement with the register bar 23 for also releasably locking the guide bars 40 to the register bar.

The device is employed in practice by removably clamping the base-plate 16 with the clamp 17 to one of the cross-bars 14 or 15 of the chase 11. The register bar 23, bar 45 22° and supporting plate 22 are applied to the base-plate 16 by arranging the parts so that the ribs 20 of the base-plate are seated in the grooves 21 of the supporting plate. The register bar 23 will then be disposed 50 across the chase 11, and crosswise of the forms of type composition 12 toward two of the opposite side bars of the frame 13 of the chase. As shown, the guide bars 25 and 26 will then be transversely disposed crosswise 55 of the chase toward the other opposite side bars of the frame of the chase. By unlocking the locks 43 of the guide bars 25 and 26 from the register bars 23 each row of the forms of type composition may then be accurately aligned in the chase according to 60 determined type measurements indicated on the scale 24 of the register bar. The forms of type composition may also be relatively arranged in transverse directions according 65 to the measurements of the scale 28 of the

guide bars. The guide bars 25 and 26 may then be locked to the register bar 23 by operating the lock 43 or operating the screw 54, and the device is used in a similar manner, as occasion requires, to line-up forms of type 70 composition in other chases.

In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope 75 thereof.

Having thus described my invention, I claim as new and desire to secure by Letters Patent:—

1. A line-up register gauge, comprising a 85 register bar adapted to be removably held within a chase so that both of its ends are disposed toward two of the opposite bars of the frame of the chase and the registering bar having an exposed scale divided into 90 type measurements, a cross guide bar adjustably movable upon one of the end portions of the register bar, and a device operable for adjusting the guide bar toward and from the center of the register bar. 95

2. A line-up register gauge, comprising a register bar adapted to be removably held within a chase so that both of its ends are disposed toward two of the opposite bars of the frame of the chase and the registering 100 bar having an exposed scale divided into type measurements, a cross guide bar adjustably movable upon one of the end portions of the register bar, a device operable for adjusting the guide bar toward and from the 105 center of the register bar, and means on the guide bar for releasably locking the bar to the register bar when the guide bar is in adjusted position.

3. A line-up register gauge, comprising a 110 register bar adapted to be removably held within a chase so that both of its ends are disposed toward two of the opposite bars of the frame of the chase and the registering bar having an exposed scale divided into 115 type measurements, two cross guide bars adjustably movable upon the end portions of the register bar and each of the guide bars having an exposed scale divided into fractions of inches, and a device operable for 120 adjusting the guide bars in unison toward and from the center of the register bar.

4. A line-up register gauge, comprising a register bar adapted to be removably held within a chase so that both of its ends are 125 disposed toward two of the opposite bars of the frame of the chase and the registering bar having an exposed scale divided into type measurements, two cross guide bars adjustably movable upon the end portions of 130

both of its ends are disposed toward two of the opposite bars of the frame of the chase and the registering bar having an exposed scale divided into type measurements, 5 two cross guide bars adjustably movable upon the end portions of the register bar and each of the guide bars having an exposed scale divided into fractions of inches, and a device operable for adjusting the 10 guide bars in unison toward and from the center of the register bar.

14. A line-up register gauge, comprising a base plate, a clamp for removably fastening the base plate to the cross bars of a 15 chase, a supporting plate adapted to be releasably held on the base plate, a register bar carried on the supporting plate so that both of its ends are disposed toward two of the opposite bars of the frame of the

chase and the registering bar having an exposed scale divided into type measurements, 20 two cross guide bars adjustably movable upon the end portions of the register bar and each of the guide bars having an exposed scale divided into fractions of inches, 25 a device operable for adjusting the guide bars in unison toward and from the center of the register bar, and means on each guide bar for releasably locking both bars to the register bar when the guide bars are in 30 adjusted positions.

This specification signed and witnessed this 17th day of October, A. D. 1921.
